[57] CLAIM

The ornamental design for a stuffed animal toy, as shown and described.

DESCRIPTION

FIG. 1 is a top, front, right perspective view of a stuffed animal toy embodying our new design;

FIG. 2 is a side elevational view of the stuffed animal toy as shown in FIG. 1;

FIG. 3 is an enlarged front elevational view of the stuffed animal toy as shown in FIG. 1; and

FIG. 4 is a partial bottom plan view thereof.
